[57] CLAIM

The ornamental design for the pocket pouch for gum, mints and toothpick, as shown in the accompanying drawings.

DESCRIPTION

FIG. 1 is a front elevational view of a pocket pouch for gum, mints and toothpick showing my new design, with the flap shown in a closed position;

FIG. 2 is a front elevational view, with the flap shown in an open position;

FIG. 3 is a top perspective view of the pouch as shown in FIG. 2; and,

FIG. 4 is a side perspective view, with the opposite side being a mirror image thereof.

The rear surface of the pouch is plain and unornamented.

The packages of gum and mints and the toothpick shown in the drawings are for environment only and are no part of the claimed design.
